Attorney.

UNITED STATES PATENT OFFICE.

JOHN DESMOND, OF DETROIT, MICHIGAN, ASSIGNOR TO NORMAN LITTLE
HAYDEN AND JOHN NORMAN DERBY, OF SAME PLACE.

STEAM-INJECTOR.

SPECIFICATION forming part of Letters Patent No. 392,544, dated November 6, 1888.

Application filed September 6, 1888. Serial No. 284,684. (Model.)

To all whom it may concern:

Be it known that I, JOHN DESMOND, a citizen of the United States of America, residing at Detroit, in the county of Wayne and State 5 of Michigan, have invented certain new and useful Improvements in Steam-Injectors, of which the following is a specification, reference being had therein to the accompanying drawings.

10 This invention pertains to certain new and useful improvements in steam-injectors, having for its object the provision of new and improved simple and highly-efficient means for readily and easily creating a vacuum in the 15 water-supply chamber for rapidly elevating or raising the water thereinto, and also the production of an injector having but few parts, which in the main are immovable.

16 The invention also comprises the details of 20 construction, combination, and arrangement of parts, substantially as hereinafter fully set forth, and particularly pointed out in the claims.

25 In the accompanying drawings, Figure 1 is a vertical longitudinal sectional view of my improved injector. Fig. 2 is a horizontal sectional view thereof on the line $x x$, Fig. 1.

Referring to the drawings, A designates the 30 tubular casting or casing, provided, as customary, with the steam-inlet arm or branch a , the water-inlet arm a' , the outlet-arm a'' , and the delivery-arm a''' , to each of which is connected the ordinary pipe by means of pipe-couplings. (Not shown.) The main or body portion of casting A is divided by walls b b' into inner exhaust and overflow chambers, b^2 b^3 , which open into and are surrounded by the main overflow-chamber B. In an aperture in the upper portion of wall b rests a valve, C, the stem of 35 which is free to work in a plug, d, screwed into the casing A, while in a similar but considerably smaller aperture of wall b' rests a second valve, C', the stem of which is likewise secured by a plug, d'. From this it will be 40 seen that the exhaust and overflow chambers have independent communications with the main overflow-chamber, and that the exhaust steam and overflow passing into said main overflow-chamber will pass between the adjacent parallel sides of walls b b' and out through arm a'' .

D is the ordinary steam-inlet jet secured in arm a , and having its inner end projecting into water-supply chamber e . The lifting-tube E is screwed or otherwise secured in an aperture 55 of internal wall, e' , and its inner end extends into exhaust-chamber b^2 , into which also projects the end of combining-tube F, screwed into wall b' of chamber b^3 , and projecting across the central portion of the overflow-chamber B. 60

G is the delivery-tube screwed into or made to form a part of the end plug, g, the aperture of which coincides with that of said tube.

From the foregoing description it will be seen that steam on being admitted to the injector will first pass out of the lifting-tube into the first or exhaust chamber b^2 , and, raising valve C, will pass out through the overflow, thus creating a vacuum in the water-supply chamber, which will immediately effect the 65 lifting of the water thereinto, and the same will be forced with the steam through the series of tubes to the boiler. At first some steam and water will pass into both the chambers b^2 b^3 , and will immediately raise their respective 70 valves and escape into the overflow. The opening of both valves from the inner chambers into the main overflow-chamber will the more readily effect a vacuum in the water-supply chamber, and thus cause the immediate establishment of the jet which will pass to the 75 boiler.

I claim as my invention—

1. As an improvement in steam-injectors, the herein-described injector having a main 80 overflow-chamber, as B, and inner exhaust and overflow chambers, b^2 b^3 , located within and surrounded by said main overflow-chamber, with which they communicate, said exhaust and overflow chambers b^2 b^3 being formed 85 as part of the casing and independent of said main overflow-chamber, substantially as set forth.

2. As an improvement in steam-injectors, the injector herein described, having the main 90 overflow-chamber, as B, the inner exhaust and overflow chambers, b^2 b^3 , located within and surrounded by said main overflow-chamber, and provided with openings or apertures, one being larger than the other, and the valves 95 designed to fit in said openings, said exhaust and overflow chambers b^2 b^3 being formed as part 100

- of the casing and independent of said main overflow-chamber, as set forth.
3. As an improvement in steam-injectors, the injector herein described, having the main overflow-chamber B, the two internal walls having adjacent parallel sides and provided with openings or apertures, one being larger than the other, and the valves designed to fit in said openings, substantially as described.
- 10 4. As an improvement in steam-injectors, the injector herein described, having the two internal walls, forming inner exhaust and overflow chambers, b^2 b^3 , and provided with coincident apertures, and the combining-tube fitted in one of said walls and projecting snugly through the aperture of the other adjacent wall, substantially as described.
- 15
5. The herein-described improved injector, comprising the casing having the main overflow-chamber B, the inner exhaust and overflow chambers, b^2 b^3 , having upper openings, the valves designed to rest in said openings, the steam-inlet jet, the lifting-tube, the combining-tube connecting said inner exhaust and overflow chambers, the delivery-tube, and the end plug to which said latter tube is secured, all constructed and arranged substantially as shown and described.

In testimony whereof I affix my signature in presence of two witnesses.

JOHN DESMOND.
